UNITED STATES PATENT OFFICE.

ERNEST W. HOPPE, OF MERTON, WISCONSIN.

SOD-CUTTER.

No. 861,119.

Specification of Letters Patent.

Patented July 23, 1907.

Application filed April 22, 1907. Serial No. 369,431.

To all whom it may concern:

Be it known that I, ERNEST W. HOPPE, a citizen of the United States, and a resident of the town of Merton, in the county of Waukesha and State of Wisconsin, have invented certain new and useful Improvements in Sod-Cutters; and I do hereby declare that the following is a full, clear, and exact description thereof.

The object of my invention is to provide a simple, durable and effective sod-cutting attachment for sulky-plows, the construction and arrangement of its parts being such that the sod is cut, elevated and thoroughly separated from any soil that may adhere to its roots and thereafter delivered to a carrier, which drops said sod from time to time in piles to be afterwards collected or destroyed.

This attachment is especially designed for effectually eradicating obnoxious grasses that cannot be destroyed by the common method of turning under.

Said invention therefore consists in various details of construction and combination of parts as herein-after fully set forth with reference to the accompanying drawings and subsequently claimed.

In the drawings: Figure 1 represents a sectional elevation of a sulky or riding plow having attached thereto a sod-cutter embodying the features of my invention, the section being indicated by line 1—1 of Fig. 2, parts of the machine being broken away to better illustrate the details; Fig. 2, a plan view of the same, with parts broken away and parts in section to more clearly show the invention, and Figs. 3 and 4 are cross-sections of the attachment, as indicated by lines 3—3 and 4—4 of Fig. 1.

Referring by letter to the drawings, A indicates the frame of an ordinary sulky-plow, which frame is supported by the usual wheels B, C, and D, the land side-wheel B being mounted upon a cranked stud axle E that is swiveled in a bracket F secured to the frame. The cranked end of the axle is raised or lowered by a hand-lever G, which lever is fast on said axle and is provided with a locking-detent arranged to engage a sector H projecting from the bracket. The raising and lowering mechanism above mentioned permits regulation of the elevation of the frame with relation to the wheel B and forms no part of my invention.

A plow-beam I is connected to the frame by links J, the beam being raised or lowered by a detented lever K, which lever is fast on a shaft L that is in crank-connection with said beam. The plow-beam carries the usual land-side plates at its lower end, and in place of the ordinary mold-board, has secured thereto a mold-board M, the face of which is horizontally inclined and terminates with an abrupt rear edge. Secured to the outer lower face of the mold-board is an angle-iron strut N, which strut together with a strut O form an elevator-frame that extends upwardly and rearward from said mold-board. The strut O is pro-

vided with a brace-piece a, which terminates at its lower end in a curved portion that merges into the said strut-body, thereby forming a curvature coinciding with the throat of the plow-beam I; to which beam said strut is secured by suitable bolts. The struts are also connected together by cross-braces b, the rear ends of said struts being braced by a yoke c, which is hung in a sleeved-bracket d fast to the plow-frame. The ends of this yoke are connected to ears e of standards f that project from said struts, there being similar pairs of standards f' at intervals throughout their length. Each of the aforesaid pairs of standards are slotted to receive bearing-blocks g for crusher-rollers h, there being interposed between the blocks suitable followers i and compression-springs j; which springs are adjustable as to tension by means of set-bolts j' that engage the followers and are threaded into the heads of the standards.

Mounted in bearings at the rear end of the elevator-frame, is a shaft K that carries a pair of sprocket-wheels m, which sprocket-wheels serve as drivers for an endless lag-chain P. The said chain, at its lower end, travels over idle-rollers n, which are located directly under the mold-board and are mounted upon a shaft o having its bearings in the elevator-frame struts. The lag-chain serves as a conveyer, whereby the cut sod is carried from mold-board and discharged into a forked carrier P' at the opposite end of the elevator-frame. The sod in its travel upon the chain passes under the several spring-controlled crusher-rollers, which serve together with a vibratory motion of said chain to beat out the soil from the roots and thus break up said sod so that it may readily be dried and destroyed.

The speed of the lag-chain is slightly accelerated over the travel of the plow and thereby cause a draw upon the sod, which action tends to break the same into blocks as it passes from said mold-board.

Drive is imparted to the lag or conveyer-chain from the land-side wheel Q secured to the hub of said wheel B and meshed with a pinion R, a stud of which pinion is mounted in a bracket S secured to the cranked axle. The pinion-stud carries a knuckle-jointed tumbler-rod T that is squared and fitted into a sleeve U, which in turn is knuckle-jointed to a shaft V, which shaft has its bearings in the elevator-struts and carries a sprocket-wheel W fast thereon. This sprocket-wheel is in link-belt connection with a similar sprocket X fast on the lag-chain drive-shaft K.

By the described drive-connection, it will be seen that the plow and elevator connected thereto may be raised or lowered with relation to the plow-frame without interfering with the driving-mechanism, the play between the parts being compensated for by the sleeve and tumbler-rod, whereby universal adjustable motion is had. The conveying or load-side of the lag-chain

P is supported at intervals by idle-rollers *n* and spools *n'* that are mounted upon shafts having their bearings in the struts constituting the elevator-frame.

- The sod-carrier P' comprises a series of tangs secured 5 to a shaft *p*, which shaft is supported in bearings of a depending arm of the strut N, there being a coiled spring *p'* secured to the shaft, having one end looped under an adjacent fork-tang and the opposite end thereof engaging the depending strut-arm. The spring *p'* 10 serves to support the carrier and load, said carrier being prevented from rising above a vertical position by a stop *p''*, which projects in the path of an adjacent tang of the aforesaid carrier. The carrier-shaft is in universal slip-joint connection with a rod *q* that has 15 a forward bearing in a bracket fast to the frame A, there being a foot-treadle *r* fast on the end of the rod whereby the driver may, at will, cause the carrier to drop the sod accumulated thereon. From the foregoing it will be seen that the sod drops outside of 20 the line of the next furrow and is not covered thereby, the universal slip-joint connection permitting adjustment of the plow with relation to the frame, it being understood however that any form of dumping-carrier 25 may be substituted for that shown.
- An outwardly curved deflector *t* is secured to the strut N and extends throughout the length of the elevator-frame. This deflector serves to catch the loose dirt as it is freed from the sod in its upward travel and delivers said dirt outside of the line of cut of the plow, 30 or clear of the unbroken ground.
- From the foregoing described mechanism it will be understood that the sod-cutting attachment may readily be applied to sulky-plows of ordinary construction, it being only necessary to attach the elevator-frame to 35 the plow-beam and brace the same by the swinging yoke, the gear - wheel, pinion and accompanying bracket S being secured to the cranked axle. This ar-

angement of the attachment does not in any way interfere with the freedom in adjusting the plow to different depths of cut, as would be required either in 40 plowing or sod-cutting. When the attachment is disconnected from the plow, it is apparent that the usual mold-board must be substituted for that shown.

I claim:

1. In a plow, having a wheel-supported frame and a 45 plow-beam in adjustable connection with the frame, the combination of an inclined elevator-frame in rigid connection with the plow-beam, shafts supported in the elevator-frame at either end thereof, sprocket-wheels carried by one of said shafts, idle-rollers mounted upon the opposite 50 shaft, an endless conveyer-chain carried by the sprocket-wheels and idlers, spring-controlled crusher-rollers mounted in said elevator-frame above the conveyer-chain, and a driving-mechanism for the conveyer-chain in connection with one of the wheels of the plow-frame. 55

2. In a plow, provided with a supporting-frame, and a plow-beam in adjustable connection with said frame, the combination of an inclined elevator-frame in rigid connection with the plow-beam, a traveling conveyer-chain carried by the elevator-frame, compressed crusher-rollers 60 above the conveyer-chain, driving-gears for said conveyer-chain in adjustable connection with one of the supporting-wheels of the plow-frame, a swinging-yoke connecting the said elevator and plow frames, and a dumping-carrier in connection with the rear or discharge-end of the aforesaid elevator-frame. 65

3. In a sulky-plow provided with a frame, supporting-wheels therefor, and a plow-beam in adjustable connection with the frame; the combination of an attachment comprising an inclined elevator-frame in rigid connection with the plow-beam, an endless conveyer-chain carried by the elevator, and driving-means for the chain in universal adjustable connection with said elevator-frame and one of the supporting-wheels. 70

In testimony that I claim the foregoing I have hereunto 75 set my hand at Milwaukee in the county of Milwaukee and State of Wisconsin in the presence of two witnesses.

ERNEST W. HOPPE.
